UNITED STATES PATENT OFFICE.

CHARLES DE MINICO, OF BOSTON, MASSACHUSETTS, ASSIGNEE TO UNITED SHOE MANUFACTURING CORPORATION, OF PATERSON, NEW JERSEY, A CORPORATION OF NEW JERSEY.

MACHINE FOR WORKING UPPERS OVER LASTS.

Application filed September 25, 1919. Serial No. 326,175.

The invention relates to machines for working uppers over lasts in the manufacture of boots and shoes, and in many of its aspects has reference more particularly to machines for pulling uppers over lasts.

A feature of the invention consists in a novel organization of means for controlling the application of pressure in the operation of laying the margin of an upper inwardly over the sole or insole of a shoe. In one of its aspects the invention has in view an organization wherein the shoe receives a comparatively light overlaying pressure in the inward movement of the overlaying means 10 or in the first portion of such movement, and wherein the pressure is increased by relative movement of the shoe and the overlaying means while said means is positioned over the bottom of the shoe. One important advantage of such an organization is to be recognized in operation upon shoes having comparatively flexible or yielding insoles such, for example, as the type of shoe herein illustrated, commonly known as an "arctic" shoe, in which the insole comprises a composition of unvulcanized rubber. By moving the overlaying means inwardly across the outer edge of the insole of such a shoe with light overlaying pressure insurance is afforded that the margin of the insole will not be pressed back from the edge of the last bottom or otherwise displaced. In the pulling-over machine organization illustrated the overlaying means comprises wiper 20 members mounted on toe and side tacker arms which are moved inwardly after the upper has been pulled to lay the margin of the upper over the insole and which also carry tackers for fastening the upper in overlaid position, and the shoe is positioned relatively to said members to receive the light overlaying pressure by depression of the sole rest. After the overlaying members in 30 the construction shown have advanced across the outer edge of the insole, and it may be substantially at the time when the grippers are tripped to release the upper and before the overlaying members have completed their inward movement, increased overlaying pressure is brought to bear on the margin of the upper by relative movement between the overlaying members and the shoe, such movement in the construction herein shown resulting from a retractive movement 40 of the sole rest, permitting the shoe to react

against the overlaying members and to be pressed toward said members also by reaction of a yielding shoe support which sustains the shoe against the overlaying pressure. In this manner the upper is held effectively against loss of the pulling-over tension and is pressed firmly into position to receive the fastening tacks.

The above and other features of the invention, including also a novel construction and arrangement of fastening mechanism and certain details of construction and combinations of parts, will now be described with reference to the accompanying drawings and pointed out in the claims.

In the drawings,

Figure 1 is a view in side elevation of a pulling-over machine in which the invention is embodied;

Fig. 2 is a perspective view illustrating the relation of the pulling-over means and of the overlaying and fastening means to a shoe;

Fig. 3 illustrates further the relation of the side grippers to the contour of the shoe and indicates also the points at which the tacks are driven in the illustrative machine;

Fig. 4 shows the overlaying and tacking mechanism at one side of the shoe at an intermediate stage in its inward movement, illustrating the depression of the shoe to afford clearance for the overlaying wipers;

Fig. 5 shows the wipers at their inner limit of movement with the shoe pressed up against then in consequence of retraction of the sole rest;

Fig. 6 is a perspective view showing the overlaying and fastening means at one side of the shoe in its operative relation to the shoe;

Fig. 7 shows in perspective one of the side tackers and its associated overlaying mechanism detached, and

Fig. 8 is a diagrammatic view of the sole rest operating cam.

The invention is herein illustrated as embodied in a well known type of pulling-over machine the general characteristic features of which are shown and described in detail in various prior United States Letters Patent including particularly Patent No. 1,029,387, granted on June 11, 1912 upon an application of R. F. McFeely, and in view of such prior disclosure the details of construction of the illustrative machine, in so

far as they are not modified for the purposes of this invention, will be described only in brief terms. For purposes of illustration, moreover, the invention is herein shown in its application to a machine embodying features particularly designed for operation upon arctic shoes or shoes of similar type, as described and claimed in United States Letters Patent No. 1,501,053 granted on July 15, 1924 upon an application of Bernhardt Jorgensen. It is to be understood, however, that the invention in many of its aspects is not limited to machines of the particular type illustrated.

The machine comprises in its general organization a toe gripper 2 connected to an updraw lever 4, side grippers 6 connected to updraw levers 8, means comprising cam slides 10 and 12 operated by cams on a cam shaft 14 for imparting operative movement through springs 16 to the levers 4 and 8 respectively for pulling the upper over the last against the resistance of a sole rest 18, side clamp arms 20 which carry yieldable presser pads 22 and are swung inwardly into supporting and holding engagement with the shoe, and overlaying and tacking devices for the toe and the opposite sides of the forepart of the shoe carried respectively by a toe tacker arm 24 and side tacker arms 26. In the operation of machines of this type the starting of the machine is followed by closing and updraw movement of the several grippers accompanied also by a slight depression of the sole rest 18 against the pressure of its return spring 25 through the operation of a cam 28 on the end of the cam shaft 14 upon a roll 30 which is mounted on the pivoted sole rest carrier 32. After the upper pulling operation the machine comes to rest to permit inspection of the work and any adjustment which may be necessary. When the machine is again started the side clamp arms 20 are swung into supporting and holding engagement with the forepart of the shoe and either immediately thereafter or following a second pause in the operation of the machine, the grippers are forced yieldingly inward over the shoe bottom to overdraw the upper and the several overlaying and tacking devices also are moved inwardly, these devices finally causing the grippers to release the upper by engagement with tripping devices 27 and then driving the upper fastening tacks, the mechanism for effecting the overdraw movement of the overlaying and tacking devices not being shown herein in detail since it is fully illustrated and described in the prior McFeely patent above mentioned.

In the machine herein shown the side grippers comprise, in addition to gripper jaws 34 which are arranged to engage the upper substantially at the location of the usual tip seam, a pair of gripper jaws 36

positioned at each side of the last at the rear of the jaws 34 and constructed for continuous engagement with a portion of the margin of the upper extending along the ball of the last and thence rearwardly toward or into the shank. As illustrated in Figs. 2 and 3, the rear portions of the jaws 36 are curved inwardly in substantial conformity to the inward curve of the edge of the last bottom at the rear end of the ball of the last, and as shown also more particularly in Fig. 3 the outer edges of these jaws are likewise curved in substantial or approximate conformity to the lengthwise slope of the last bottom from the ball rearwardly into the shank, the rear ends of the jaws thus extending downwardly into position for convenient engagement with the margin of the upper along its receding edge line as well as into position to insure effectiveness of the gripper in the upper pulling and overdrawing operations upon portions of the upper at and adjacent to the rear end of the ball of the last. As thus constructed the side grippers position and hold the upper substantially as close to the lateral periphery of the last adjacent to the edge of the last bottom along the inwardly curved portion of the surface of the last at and adjacent to the rear end of the ball as they do in relation to portions of the last extending farther forwardly along the forepart, and in the overdrawing operation portions of the upper at and beyond the rear end of the ball are drawn inward over the margin of the insole substantially as far and with as hard a pull as the other portions of the upper which are engaged by the side grippers, with the result that the pulling-over operation is rendered adequately effective along the entire forepart of the shoe as far back as the shank.

The overlaying and tacking mechanism carried by the toe tacker arm 24 may be and is herein shown as of substantially the same construction as illustrated in the McFeely patent before mentioned and more in detail as to certain features of the overlaying mechanism in Patent No. 1,135,954, granted on April 13, 1915 upon an application of R. F. McFeely, and comprises a yieldable overlaying wiper 38, a tack holder 40 and a tack driver 42. The construction herein illustrated is adapted for driving a single tack at the end of the toe, but it will be understood that the number and arrangement of the toe tacks may be varied as desired. Portions of the side overlaying and tacking devices carried by the side tacker arms 26 are also shown as of substantially the same construction as in said prior patents, such devices comprising a pair of overlaying wipers 44 at each side of the shoe having upturned inner ends to guide them over the edge of the shoe bottom and yieldingly

- controlled as to rocking and lengthwise movements by means of a spring 46, and tack holders 48 and 50 with corresponding tack drivers 52 operated by a driver bar 54.
- 5 As illustrated, the tack holder 48 is arranged to hold two tacks in position to be driven by the corresponding pair of tack drivers, these tacks being arranged to be applied to the shoe at or near the location of the tip seam
- 10 where the shoe is provided with a tip, and the tack holder 50 with its corresponding driver is arranged for inserting a tack a short distance at the rear of the tip seam location. It will be understood that the
- 15 tack holders 48 and 50 with the corresponding drivers are swiveled for turning movement in accordance with the lengthwise contour of the edge of the shoe bottom, the extent of projection of these tackers over the
- 20 shoe bottom being determined by a plate 56 located under the tack block and arranged to engage a stop 58 on the underlying side clamp arm.
- In the construction herein shown there is
- 25 provided also means for overlaying a portion of the margin of the upper at each side of the shoe in the rear of the wipers 44 and extending over and beyond the rear end of the ball of the last, together with means
- 30 for driving a tack at each side at or near the rear end of the ball. For this purpose there is secured to each side tacker arm 26 a plate 60 which carries a pivot rod 62 on which is mounted a plate 64 for swinging
- 35 movement transversely of the edge of the shoe bottom. The plate 64 carries near its lower end a tack holder 66 which is herein shown as constructed substantially as illustrated in United States Letters Patent No.
- 40 1,279,491, granted on September 24, 1918, upon an application of Orrell Ashton. Associated with the tack holder 66 is a driver 68 arranged to be operated by a swinging arm 70 which is pivoted on the plate 64
- 45 and slotted to receive a pin 72 projecting from the driver bar 54 for imparting operative movement to the driver 68. A spring 74 connected at one end to a pin on the plate 64 and at its other end to a pin 76 pro-
- 50 jecting through a slot in the plate 64 tends to swing the latter plate and its supported tack holding and driving means toward the shoe, the position of the plate relatively to the shoe and the consequent extent of pro-
- 55 jection of the tack holder over the shoe bottom being determined by a stop 78 on the front of a plate 80 which is secured adjustably by means of a screw and slot connection 82 to the lower end of the plate 64. The
- 60 rearmost tacker thus adjusts itself automatically relatively to the edge of the shoe bottom for driving its tack at a predetermined distance from the edge. In the construction shown and in accordance with this
- 65 invention the position of the rearmost tack

lengthwise of the edge of the shoe bottom may be adjusted, as for different sizes of shoes, by means of a nut 84 against which the plate 64 is normally pressed by means of a spring 86 on the pivot pin 62.

Pivots mounted on the lower end of the plate 64 below the tack holder 66 are a pair of overlaying members 88 which in view of their usual characteristic function may be conveniently termed wipers, these members

70 in the construction shown having at their front ends rolls 90 to assist in eliminating undesirable frictional pressure of the members against the shoe materials at the edge

75 of the shoe bottom. Springs 92 connected respectively to the rear ends of the members 88 and to pins on the plate 64 tend to swing these members about their pivots in a direction for applying holding pressure to the

80 margin of the upper over the shoe bottom while permitting them to yield each independently of the other in response to resistance of the shoe materials, the normal position of the members being adjustably

85 determined by stop screws 94 which are carried by the plate 80 and arranged to engage underneath the members 88 in front of their pivotal axes. It will be noted that the

88 overlaying members or wipers 88 are located respectively at opposite sides of the tack

90 holder 66 and closely adjacent to the tacking point, the foremost member being arranged to engage a portion of the upper over the ball of the last and the rearmost mem-

95 ber to engage a portion of the upper over the receding curved portion of the last bottom beyond the rear end of the ball. With this

100 arrangement of the members, the provision for independent yield of each member trans-

versely of the plane of the shoe bottom has important advantages, since it permits both

105 members to operate with equally effective results to hold the stock notwithstanding the differences in contour of the different por-

110 tions of the last bottom over which the re-

115 spective members operate, and the provision for separate adjustment of the different members is also of advantage in adapting

120 the mechanism to different shapes of shoes.

In order to avoid undesirable pressure of

125 the toe and side wipers 38 and 44 and of the members 88 against the upper opposite to the edge face of the sole or insole such as

130 might tend to double up or otherwise dis-

135 place the margin of a flexible or yielding insole like that herein shown, the machine is

140 provided, in accordance with this invention, with means for depressing the last prior to the advance of the several overlaying mem-

145 bers over the edge of the shoe bottom and

150 after its first depression effected as usual in machines of the illustrative type in the course of the pulling movement of the grippers. This is effected through the provi-

155 sion of a projection 96 (Fig. 8) on the sole

rest rocking cam 28 whereby the sole rest 18 is rocked about its axis from the dotted to the full line position illustrated in Fig. 4 to locate the insole in a slightly lower plane relatively to the overlaying means, after its first depression by the usual rise 98 on the cam. In the construction shown the second depression of the last takes place after the clamping and supporting pads 22 have engaged the shoe and at about the time when the tacker arms 24 and 26 begin their inward movement toward the shoe. As soon as the overlaying members have moved inwardly beyond the edge of the insole, and in the construction shown at about the time when the several grippers are tripped to cause them to release the margin of the upper, the cam 28 in its continued movement carries the projection 96 beyond its operative position, permitting the spring 25 to retract the sole rest, and permitting reaction of the side clamping and supporting devices, which are held against the shoe with comparatively heavy pressure, to force the shoe upwardly against the overlaying members, such upward movement of the shoe and its own resilience, combined with pressure of the wiper controlling springs 46 and 92 serving to insure that the margin of the upper shall be effectually clamped against the insole in such manner as to prevent reaction of the upper and consequent loss of the pulling-over tension prior to the driving of the tacks. It will be further evident that depression of the shoe after the side clamping and supporting devices have been moved to operative position assists in tightening the upper in preparation for the overlaying operation.

In the operation of the machine, briefly summarized, the operator presents a shoe with its sole or insole on the bottom of the last against the sole rest 18 and arranges the margin of the upper within the open jaws of the toe and side grippers and then starts the machine by depression of the usual starting treadle, whereupon the grippers are operated to pull the upper and the sole rest 18 is rocked downward, as usual in machines of the illustrative type, by the action of the cam projection 98 (Fig. 8) on the cam 28, the machine then coming to rest with the upper under tension to permit inspection and any necessary adjustment. Following a subsequent starting of the machine the side clamping and shoe supporting devices 22 are swung into operative engagement with the shoe. Either immediately thereafter, or following a further rest in the cycle of operations, the toe and side grippers are swung inwardly to overdraw the upper, accompanied by the toe and side tacker arms which force the several overlaying members or wipers into engagement with the tensioned upper, these

members being permitted to yield both upwardly and backwardly against the tension of their controlling springs in response to resistance of the upper still held in the grippers, as will be understood by reference to Fig. 4, the provision for backward yield of the members 88 being afforded by the springs 74. Before the overlaying members advance across the edge of the shoe bottom the last is depressed to the position illustrated in Fig. 4 by operation of the cam projection 96 on the sole rest. As the tacker arms continue their inward movement they cause the grippers finally to release the upper through engagement with the tripping devices 27, and at about the same time the retractive movement of the sole rest permits the shoe to be forced upwardly against the overlaying members by the reaction of the shoe clamping and supporting devices, thus increasing the pressure of said members on the shoe and positioning the shoe closer to the tack holders for the tacking operation. The tacker arms having completed their inward movement, and the rear-most tackers having adjusted themselves relatively to the edge of the shoe bottom, the several tacks are driven, after which the parts return to their starting positions and the shoe is released.

It will be understood that the invention is by no means limited in utility to the manufacture of shoes of the particular kind herein illustrated, but is applicable to the manufacture of various types of shoes including welt and turn shoes as well as shoes of the McKay type, and to shoes made of various materials.

In the appended claims the term "sole" is used generally for convenience to define that portion of the shoe to which the margin of the upper is fastened in lasting, irrespective of the type of shoe, and is thus inclusive of the insole of a welt or a McKay shoe as well as of the sole of a turn shoe.

Having described the invention, what I claim as new and desire to secure by Letters Patent of the United States is:

1. In a machine of the class described, the combination with last and upper positioning means, of upper pulling means constructed to engage the upper along the side of the last including a section of the upper extending beyond the rear end of the ball of the last, and upper fastening means including a tacker arranged to drive a tack substantially at the rear end of the ball of the last, said tacker being adjustable lengthwise of the edge of the shoe bottom.

2. In a machine of the class described, the combination with shoe positioning means, of upper fastening means movable transversely of the edge of the shoe bottom to operative position, and an overlaying member associated with said fastening means, said upper

fastening means and overlaying member being adjustable as a unit lengthwise of the edge of the shoe bottom.

3. In a machine of the class described, the combination with shoe positioning means and upper pulling means, of a plurality of tackers for driving tacks to fasten the upper, one of said tackers being adjustable relatively to another along the edge of the shoe bottom, and overlaying means adjustable with said last named tacker.

4. In a machine of the class described, the combination with last and upper positioning means, of pulling-over means, upper fastening means comprising a tacker, said tacker being adjustable lengthwise of the edge of the shoe bottom, and overlaying means comprising members for engaging the upper respectively at opposite sides of the tacking point and independently yieldable in response to resistance of the shoe materials, said members being adjustably movable with the tacker along the edge of the shoe bottom.

5. In a machine of the class described, the combination with means for pulling an upper over a last, of overlaying and fastening means comprising a plurality of tackers and overlaying members for each side of the shoe, said tackers and overlaying members being relatively adjustable lengthwise of the shoe.

6. In a machine of the class described, the combination with means for pulling an upper over a last, of overlaying and fastening means comprising a plurality of tackers for each side of the shoe, the rearmost tacker at each side being arranged to engage the side of the shoe to position it relatively to the shoe and adjustably movable lengthwise of the shoe relatively to the other tackers, and means for effecting such adjustment of the rear tackers.

7. In a machine of the class described, the combination with a side gripper for pulling an upper over a last, and means for causing said gripper to release the upper, of a side wiper movable bodily widthwise of the shoe to wipe the upper inwardly over the sole of the shoe after the upper is released by the gripper, means for positioning the shoe in such relation to said wiper as to receive comparatively light pressure from the wiper in the overwiping operation, and means for effecting a relative bodily movement of said wiper and the forepart of the shoe in time relation to the release of the upper by the gripper to press the margin of the upper upon the sole.

8. In a machine of the class described, the combination with means for pulling an upper over a last, of an overlaying member and a tacker movable as a unit inwardly over the bottom of the last to lay the margin of the upper over the sole at the forepart of the shoe and for fastening the upper in over-

laid position, means for positioning the shoe in such relation to said overlaying member and tacker as to receive comparatively light overlaying pressure in the overlaying operation, and mechanism automatically operative when said member is over the sole to effect a relative bodily movement between the forepart of the shoe and said overlaying member and tacker to press the upper upon the sole.

9. In a machine of the class described, the combination with grippers for pulling an upper at opposite sides of a last, of overlaying and fastening devices for the opposite sides of the shoe, supporting arms movable laterally of the shoe and on which said devices are mounted, means for positioning the shoe in such relation to said overlaying and fastening devices as to receive comparatively light overlaying pressure in the inward movement of said devices, and mechanism automatically operative when said devices are over the bottom of the shoe to effect a relative bodily movement of said devices and the forepart of the shoe to press the margin of the upper on the sole of the shoe.

10. In a machine of the class described, the combination with means for pulling an upper over a last, of a supporting arm mounted for swinging movement laterally of the shoe, a member carried by said arm for laying the margin of the upper inwardly over the sole at the forepart of the shoe, and mechanism automatically operative while said member is over the sole to effect a relative bodily movement of said member and the forepart of the shoe in a direction transverse to the plane of the sole for pressing the margin of the upper upon the sole.

11. In a machine of the class described, the combination with means for pulling an upper over a last, of wipers and tackers movable inwardly at opposite sides of the forepart of the shoe for overlaying and fastening the margin of the upper, and mechanism automatically operative when said wipers and tackers are over the shoe to effect a relative bodily movement between the forepart of the shoe and said wipers and tackers in a direction transverse to the plane of the shoe bottom to press the margin of the upper on the sole of the shoe.

12. In a machine of the class described, the combination with pulling-over means comprising a toe end gripper and opposite side grippers, and power mechanism for effecting an automatically limited relative movement between said grippers and a last to pull an upper, of an overlaying member movable inwardly over the bottom of the last at the forepart to lay the margin of the upper over the sole of the shoe, means for positioning the shoe in such relation to said overlaying member as to receive comparatively light pressure from said member

in the overlaying operation, and means for effecting a movement of the shoe toward said overlaying member while said member is over the sole to press the margin of the upper on the sole.

13. In a machine of the class described, the combination with means for pulling an upper over a last, of a wiper and a tacker movable as a unit inwardly over the bottom 10 of the last at the forepart for overlaying and fastening the margin of the upper, and mechanism automatically operative when said wiper and tacker are over the bottom 15 of the shoe to effect a movement of the shoe toward the wiper for compressing the margin of the upper.

14. In a machine of the class described, the combination with grippers for pulling an upper at opposite sides of a last, of overlaying 20 and fastener inserting devices movable inwardly at opposite sides of the forepart of the shoe to overlay and fasten the margin of the upper, and mechanism automatically operative when said devices are 25 over the bottom of the shoe to effect a movement of the shoe toward said devices for pressing the margin of the upper on the sole.

15. In a machine of the class described, the combination with means for pulling an 30 upper over a last at the toe and at opposite sides of the forepart, of an overlaying member movable inwardly to lay the margin of the upper over the sole of the shoe, a yieldable shoe support for sustaining the shoe 35 against the overlaying pressure, a sole rest to determine the relation of the plane of the shoe bottom to the overlaying member, and mechanism for causing a retractive movement of the sole rest to render the shoe support effective to move the shoe toward said member for compressing the margin of the upper.

16. In a machine of the class described, the combination with grippers for pulling an 45 upper at opposite sides of a last, of side wipers and tackers movable inwardly over the shoe, side clamping and supporting devices for sustaining the shoe yieldingly against the overlaying and tacking pressure, 50 a sole rest, and mechanism for causing a retractive movement of said sole rest when the wipers are positioned over the shoe to permit the shoe to be forced against the wipers by the action of the yieldable clamping and 55 supporting devices.

17. In a machine of the class described, the combination with means for pulling an upper over a last at the toe and at opposite 60 sides of the forepart, of a member movable inwardly to lay the margin of the upper over the sole at the forepart of the shoe, a support for sustaining the shoe yieldingly against the overlaying pressure, a sole rest, and means for moving said sole rest to 65 press the shoe on said support prior to the

overlaying operation and for effecting a retractive movement of the sole rest when said member is positioned over the sole to permit the shoe to be forced reversely against the overlaying member by reaction of the 70 shoe support.

18. In a machine of the class described, the combination with means for pulling an upper over a last, of overlaying and fastening means movable inwardly over the shoe 75 for overlaying and fastening the margin of the upper, side clamping and supporting devices movable inwardly after the upper pulling operation into position to sustain the shoe yieldingly against the overlaying 80 pressure, a sole rest, mechanism for moving said sole rest to depress the shoe after said side clamping and supporting devices have been moved into operative relation to the shoe and prior to the overlaying operation, and 85 additional means for effecting a reverse movement of the sole rest when said overlaying means is positioned over the sole to permit the shoe to be forced against the overlaying means by reaction of the side clamping 90 and supporting devices.

19. In a machine of the class described, the combination with means for pulling an upper over a last, of overlaying and fastening means movable inwardly over the forepart of the shoe, a shoe support, a sole rest, and an operating cam for said sole rest constructed to move the sole rest for depressing the shoe prior to the inward movement of 95 said overlaying and fastening means and to cause a reverse movement of the sole rest while said overlaying and fastening means is positioned over the shoe.

20. In a machine of the class described, the combination with grippers and means 100 for operating them to pull an upper over a last, of overlaying means mounted for movement inwardly to lay the margin of the upper over the sole, a sole rest, means for operating said sole rest to press the last into 105 the upper during the upper pulling movement of said grippers and for imparting to the sole rest a further movement in the same direction after the grippers have completed their upper pulling movement to position 110 the shoe relatively to the overlaying means, and additional mechanism for causing a reverse movement of the sole rest when said overlaying means is positioned over the bottom of the shoe for pressing the margin of 115 the upper on the sole.

21. In a machine of the class described, the combination with means for pulling an upper over a last, of wipers and tackers movable inwardly over the shoe to overlay and fasten the margin of the upper, a shoe support for sustaining the shoe against the overwiping and tacking pressure, a sole rest, and mechanism for moving said sole rest to depress the shoe in successive steps prior to 120 125 130

the overlaying operation and to cause a reverse movement of the sole rest while said wipers and tackers are positioned over the shoe.

- 5 22. In a machine of the class described, the combination with a toe gripper and opposite side grippers and means for operating said grippers to pull an upper over a last, of a wiper and a tacker movable lengthwise of the shoe at the toe for overlaying and fastening the margin of the upper, additional wipers and tackers movable laterally of the shoe at opposite sides of the forepart, a sole rest, means for operating said sole rest to depress the shoe relatively to said wipers and tackers prior to the overwiping operation, and additional means to cause a reverse movement of the sole rest while said wipers and tackers are positioned over the shoe.

20 23. In a machine of the class described, the combination with last and upper positioning means, of means for pulling the upper over the last at the end of the toe and at opposite sides of the forepart, overlaying means movable inwardly over the margin of the shoe bottom, and means for effecting after the upper pulling operation a relative movement of said last and upper positioning means and overlaying means into position to afford substantial clearance at the edge of the sole for said last-named means in its overlaying movement and for subsequently causing a relative reverse movement of said parts to cause pressure to be applied to the shoe by the overlaying means.

25 24. In a machine of the class described, the combination with upper pulling means, of overlaying and tacking mechanism for the forepart of the shoe, means for positioning a shoe in such relation to said overlaying and tacking mechanism as to permit said mechanism to move inwardly over the margin of the sole of the shoe without substantial pressure against the edge of the sole, and means constructed and arranged to cause a relative movement of said overlaying and tacking mechanism and shoe positioning means in a direction transverse to the plane of the shoe bottom while said mechanism is positioned over the shoe bottom to cause the upper to be pressed upon the margin of the sole.

30 25. In a machine of the class described, the combination with upper pulling means, of overlaying means movable inwardly over the shoe bottom and automatically operative to cause said upper pulling means to release the upper, means for positioning the shoe in such relation to said overlaying means as to avoid substantial pressure of said means against the edge of the sole in its inward movement, and means constructed and arranged for operation substantially at the time when said pulling means releases the

upper to cause a relative movement of the shoe and the overlaying means for pressing the margin of the upper against the sole.

35 26. In a machine of the class described, the combination with pulling over means, of overlaying means movable inwardly over the margin of the sole at the forepart of the shoe, a sole rest and means for operating it to depress the shoe relatively to said overlaying means after the upper pulling operation and before said means advances across the edge of the sole, and means for subsequently retracting said sole rest to permit the shoe to be forced reversely against said overlaying means.

40 27. In a machine of the class described, the combination with shoe positioning means, of overlaying and fastening devices movable inwardly over the shoe bottom at the forepart of the shoe, means for moving the shoe relatively to said devices into position to avoid substantial pressure of said devices against the edge of the sole in their inward movement, and means for causing the shoe to be forced reversely against said devices after they have moved inward across the edge of the shoe bottom.

45 28. In a machine of the class described, the combination with means for pulling an upper over a last, of toe and side overlaying devices movable respectively lengthwise and laterally of the shoe at the forepart to lay the margin of the upper inwardly over the sole, means for moving said toe and side overlaying devices inwardly over the shoe and for causing the upper pulling means to release the upper in time relation to the inward movement of said devices, and mechanism automatically operative independently of the inward movement of said overlaying devices to effect a relative movement between said devices and the shoe in a direction transverse to the plane of the sole to press the margin of the upper upon the sole.

50 29. In a machine of the class described, the combination with means for pulling an upper over a last, of opposite side wipers supported independently of each other for movements laterally of the shoe, means for moving said wipers inwardly over the shoe and for causing the upper pulling means to release the upper in time relation to the inward movement of said wipers, and mechanism automatically operative independently of the inward movement of said wipers to effect a relative movement between the wipers and the shoe in a direction transverse to the plane of the shoe bottom to press the margin of the upper upon the sole of the shoe.

55 30. In a machine of the class described, the combination with upper pulling means automatically operative to pull an upper over a last and to come to a stop with the upper held under tension, of toe and side

overlaying devices movable respectively lengthwise and laterally of the shoe to lay the margin of the upper inwardly over the sole of the shoe upon a subsequent starting 5 of the machine, and different mechanisms automatically controlled to effect respectively an inward movement of said devices over the shoe and a relative movement between said devices and the shoe in a direction 10 transverse to the plane of the sole to press the margin of the upper upon the sole.

31. In a machine of the class described, the combination with means for pulling an upper over the forepart of a last, of overlaying and fastener inserting devices movable inwardly at opposite sides of the shoe for laying the margin of the upper over the sole and for fastening it in overlaid position, means for imparting inward movement 20 to said overlaying and fastener inserting devices, and mechanism automatically operative independently of the inward movement of said devices to effect a relative movement between said devices and the shoe in a direction 25 transverse to the plane of the sole to press the margin of the upper upon the sole.

32. In a machine of the class described, the combination with power operated means for pulling an upper over a last, of upper

fastening means comprising tack holders and drivers movable inwardly at opposite sides of the shoe, means for operating said drivers in time relation to their inward movement to drive the tacks, and mechanism automatically operative prior to the driving 35 of the tacks to effect a relative movement between the shoe and said tack holders in a direction transverse to the plane of the shoe bottom to position said tack holders in closer relation to the shoe. 40

33. In a machine of the class described, the combination with means for pulling an upper over a last at the toe and at opposite sides of the forepart, of upper fastening devices comprising tack holders and drivers 45 movable respectively lengthwise and laterally of the shoe into position for fastening the upper at the toe and at opposite sides of the forepart, and mechanism automatically operative to effect a relative movement 50 between the shoe and said tack holders in a direction transverse to the plane of the shoe bottom to position said tack holders in closer relation to the shoe for the tacking operation.

In testimony whereof I have signed my 55 name to this specification.

CHARLES DE MINICO.
